UNITED STATES PATENT OFFICE.

SOREN J. NORRE, OF CHICAGO, ILLINOIS.

PROTECTOR FOR TIMER-WIRES.

1,287,734.

Specification of Letters Patent. Patented Dec. 17, 1918.

Application filed March 30, 1918. Serial No. 225,768.

To all whom it may concern:

Be it known that I, SOREN J. NORRE, a citizen of the United States, residing at Chicago, in the county of Cook and State of Illinois, have invented certain new and useful Improvements in Protectors for Timer-Wires, of which the following is a specification.

This invention relates to improvements in 10 Ford timer wire protectors and its prime object is to provide novel means for protecting the wires of Ford automobile timers. A further object is to provide a device of this class that is simple and cheap to manufacture and very efficient in use. With the foregoing and other objects in view the invention consists in the combination and arrangement of parts to be hereinafter fully described, pointed out in the appended 15 claims and illustrated in the accompanying drawing which forms a part of this specification and in which—

Figure 1 is a view in perspective of a 20 Ford timer equipped with my improved wire protector.

Fig. 2 is a view of Fig. 1 in side elevation.

Like reference characters denote corresponding parts in both views.

The reference numeral 1 denotes the timer 25 body having the usual binding posts 2 for its several wires 3 and to one of the said binding posts I secure the angular bracket 4, one end of the said bracket 4 resting upon the beveled surface of the timer body, said bracket being secured to or made integral with the tubular coupling 5 which is threaded interiorly to receive the threaded end of the flexible hose 6. The said coupling 5 is formed with a plurality of perforations 30 in its base portion which receive and retain the ends of the insulating tubes 7 which serve as conduits for the said wires 3. Rubber links 8 also serving as conduits for the wires 3 may be provided upon the ends of 35 the said tubes 7.

By means of my improved protector the timer wires 3 are protected from their points of contact with the binding posts to their association with the flexible tube or conduit 6 through which they pass to the magneto. 50

What is claimed is:—

1. In a protector for timer wires, a coupling, means for binding said coupling to one of the timer binding posts, and conduits carried by said coupling and leading to the 55 binding posts.

2. In a protector for timer wires, a coupling formed with a plurality of perforations in its base, means for binding said coupling to one of the timer binding posts, 60 and conduits terminally anchored in the perforated portions of said coupling and leading to the binding posts.

3. In a protector for timer wires, an angular bracket carried by one timer binding 65 post, a coupling formed with a plurality of perforations in its base and carried by said bracket, and conduits terminally anchored in the perforated portions of said coupling and leading to the binding posts. 70

4. In a protector for timer wires, an angular bracket carried by one timer binding post with its free end resting against the timer body, a tubular coupling formed with a plurality of perforations in its base and 75 carried by said bracket, conduits terminally secured in the perforated portions of said coupling and leading toward the binding posts, and rubber extensions for said conduits. 80

In testimony that I claim the foregoing as my own I have hereto affixed my signature in the presence of two subscribing witnesses.

SOREN J. NORRE.
